UNITED STATES PATENT OFFICE.

WAYNE W. CORE AND ALPHONSE P. WEHNER, OF PITTSBURGH, PENNSYLVANIA.

FUEL-MIXER.

1,271,541.

Specification of Letters Patent.

Patented July 9, 1918.

Application filed September 25, 1916. Serial No. 122,021.

To all whom it may concern:

Be it known that we, WAYNE W. CORE and ALPHONSE P. WEHNER, residents of Pittsburgh, in the county of Allegheny and State 5 of Pennsylvania, have invented a new and useful Improvement in Fuel-Mixers, of which the following is a specification.

This invention relates to fuel mixers for explosive engines. An object of the invention is to provide a device which will automatically supply air to be mixed with the fuel charge between the carbureter and the explosion chamber. A further object is to provide such a device of a form which will 10 automatically graduate the amount of air to be supplied in proportion to the amount of fuel which is being used by the engine. A further object is to so connect the mixer that it will be constantly and automatically lubricated by oil from the crank case. A further object is to provide a spring for actuating a piston valve in a mixer of the class described of such form that it will be readily compressed throughout a portion of its 15 length, and then the remainder of the spring will be acted upon by additional pressure and fully compressed. A further object is to provide such a device of simple construction, of few parts, and of completely automatic operation.

These and other objects are attained by a construction which is illustrated in the accompanying drawings. Figure 1 is a side elevation of the casing which incloses the 20 working parts of the mixer; Fig. 2 is a central vertical section through the device showing the normal seated position of the valve, the engine not running; Fig. 3 is a partial section similar to that shown in Fig. 2, showing the valve in raised position with the engine running; Fig. 4 is a partial vertical section on the line 4-4 of Fig. 2; Fig. 5 shows the special form of spring used in the mixer. Fig. 6 is a diagrammatic elevation 25 showing the connection of the mixer to the crank case of an explosive engine; and Fig. 7 is a diagrammatic elevation showing the connection of the mixer to the breather tube of an engine crank case.

In explosive engines, and particularly those used for high speed work, such as automobiles, motor boats, aeroplanes, etc., it has been found that the average mixture of fuel provided by drawing air through a carbureter containing gasoline, or other liquid 30

fuel, may be improved in quality by the addition of a certain amount of air. The combustion is more perfect, and the power obtained greater, when this is done.

The present invention comprises a casing 1, which may be cast in one piece. This has a threaded connection 2 adapted to engage a pipe forming an air inlet. This is preferably led to the inside of the crank case, as shown in Fig. 6 or to the breather tube, as 35 shown in Fig. 7, for reasons which will be more fully explained below. Another threaded extension 3 is adapted to be engaged by a pipe leading to the fuel supplying manifold, or to the fuel pipe between the 40 carbureter and the explosion chambers of the engine at any desired point. The casing forms a cylindrical bore 4, and has an inner wall 5 which forms a supplementary chamber 6 leading into the extension 3, which is 45 divided by a longitudinal partition 7, forming a lower chamber 8, which connects with the main bore 4 by a port 9, which is preferably T-shaped. A piston 10 is accurately fitted in the bore 4, so that it is slidable 50 therein. The central portion of this piston is cut away to form an annular passage 11, and the upper part has a cavity 11^a adapted to form a retaining seat for a coil spring 12 which bears at its other end against the top 55 of the main casing 1. The lower end of the bore is closed by a threaded cap member 13, having a small hole therethrough, the inner end of which forms a shoulder 14, upon which the slidable piston seats at the lower 60 end of its travel. The coil spring 12 is made of two parts, a larger and stronger spring 12^a, and a smaller weaker spring 12^b, the two 65 being brazed together, as shown in Fig. 5. The two parts of this spring are so selected 70 as to strength that the smaller portion 12^b will be completely collapsed before the larger portion 12^a will be materially affected. This 75 gives a preliminary resistance, and then a stronger secondary resistance to pressure on 80 the ends.

Fig. 6 illustrates in a diagrammatic manner the way in which our device is connected to the crank case of an explosive engine. As is well known, the ordinary explosive engine 85 comprises a cylinder 16, a cylinder head 17, and an intake manifold 18, connected to the inlet valves for each of the cylinders, a carbureter device 19 being fitted in a connection 90 between the intake manifold 18 and a gaso- 95

lene supply tank 20; filled by a pipe 21 leading to the main fuel storage tank. Between the cylinders the engine has a crank case 22, and ordinarily breather tube 23 is used for allowing equalization of the air in the crank case, or as a port for pouring oil thereinto. Our mixer is either screwed into the inlet manifold by the extension 3, or by means of a connecting pipe, and the extension 2 is connected by a pipe 24 to the engine crank case, as shown in Fig. 6. Or, if preferred, this pipe 24^a may be connected to the breather tube, as shown in Fig. 7, and thus cutting into the crank case is avoided.

The operation of the device is as follows:—The mixer being connected through outlet 3 to the manifold or fuel supply pipe beyond the carburetor, when the engine starts, the exhaust created by the induction stroke of a piston, creates a partial vacuum which is applied through the chamber 6 and bore 4, tending to raise the piston valve 10 in the casing. It will be observed that in the normal position of this piston, that is at the bottom of the casing, there is a slight leakage from the inlet pipe 2 to the space provided by passage 11 around the piston, consequently the exhaust or suction of the cylinder immediately forces the piston upward to the limit of its travel in that direction, as shown in Fig. 3. In this position, the passage through the casing is entirely closed, and no air is supplied to the manifold. As the engine gets started, the throttle is opened wider, allowing the passage of more gas through the carburetor, and consequently the strength of the partial vacuum is reduced, whereupon the spring 12 tends to force the piston 10 downward. This brings the edge 15 of the passage 11 of the piston below the top of the port 9 through the casing wall into the outlet connection 3, and air is drawn through the casing and mixed with fuel in the fuel supply manifold.

As more gas is supplied to the engine, the vacuum further decreases, the piston further descends, to a position which allows the entire opening 9 to register with the passage 11, and the maximum amount of air is supplied through the mixer, and combined with the fuel supplied to the explosion chambers. It will be understood that the normal position of the piston while the engine is running is with a portion of the port 9 registering with the passage 11. As the amount of fuel supplied varies, the force of the partial vacuum varies directly, and the piston is moved up and down, as the forces of the spring and exhaust change. Consequently the supply of air varies directly as the amount of fuel supplied to the engine, and the mixture is substantially constant.

The port 9 is preferably made in the form of an inverted T, which shape provides for the passage of a small amount of air at the

time the engine is starting, and then gives a much greater amount as the maximum amount of fuel is reached.

The inlet extension 2 may be simply an opening into any free air space, but it is preferred to lead a pipe therefrom to the crank case of the engine. This draws an oil-saturated air through the mixer which forms an efficient means of lubrication for the piston 10, and secures an air free from dust and particles of solid matter. In addition to this, there is a certain amount of gas in the case, escaped from the cylinder which is usable for explosives. In some cases it is not desirable to bore into the crank case of an engine, and then this connection may be made to the breather tube, giving substantially the same results.

The particular form of coil spring, to oppose the upward travel of the piston permits a very ready movement for the first half of its travel, and opposes a much greater resistance during the second half. This second half of its path of travel comprises that portion which varies as the amount of fuel supplied to the engine is changed. Consequently the valve very quickly moves to operative position, and then its variation in actual use is determined by a much stronger spring.

It will be observed that the device is very simple in construction, and that the casing may be made a single casting. The diaphragm 7 is not absolutely essential to the operation, and when used it may be made by the simple insertion of a strip of metal. There are only two movable parts, including the spring, and there is no need for adjustment, and in fact no parts to be adjusted or which can work out of adjustment. Other advantages will be apparent to those familiar with the art.

We claim:

1. The combination with an explosive engine, of an air supply device comprising a casing having a sliding valve therein, means to move the valve by exhaust of pressure in the engine fuel supply manifold to allow air to pass through the casing, and connections through the casing to the engine crank case and to the fuel supply manifold.

2. In a device of the class described, a casing having a passage therethrough connected on one side to the fuel supply pipe and on the other to the crank case of the engine, a piston valve in the casing controlling the passage, and means to actuate the piston automatically governed by the amount of fuel supplied to the engine, the passage being graduated to increase the supply of air as the speed of the engine increases.

3. A fuel mixer for explosive engines, comprising a casing adapted to be connected to the fuel supply manifold on one side and to the crank case on the other, and a piston

valve in said casing controlling the passage therethrough and arranged to automatically govern the passage of air to increase the supply of air as the speed of the engine increases.

4. A fuel mixer for explosive engines, comprising a casing adapted to be connected to the fuel supply manifold on one side and to the crank case on the other, a piston 10 slidably mounted in the casing and having an annular channel adapted to register simultaneously with said connections, a spring normally holding the piston in position to close the connections, and automatic 15 means to move the piston to permit passage of air through the casing to the supply manifold, the supply of air being increased as the speed of the engine increases.

5. The combination with an explosive engine, of an air supply device comprising a 20 casing having a sliding valve therein, a graduated opening through the casing, means to move the valve by exhaust of pressure in the fuel supply manifold of the engine to allow discharge of air through the 25 casing, and connections through the casing to the engine crank case and fuel supply manifold.

In testimony whereof, we have hereunto set our hands.
